UNITED STATES PATENT OFFICE.

FRANK MANSFIELD, OF NEW YORK, N. Y.

ELECTRIC SWITCH FOR ELECTRIC RAILWAYS.

SPECIFICATION forming part of Letters Patent No. 450,172, dated April 14, 1891.

Application filed November 18, 1890. Serial No. 371,822. (No model.)

To all whom it may concern:

Be it known that I, FRANK MANSFIELD, a citizen of the United States, residing at New York, county and State of New York, have 5 invented certain new and useful Improvements in Electric Switches for Electric Railways, of which the following is such a full, clear, and exact description as will enable any one skilled in the art to which it appertains 10 to make and use the same, reference being had to the accompanying drawings, forming part of this specification.

My invention relates to an electric switch for connecting and disconnecting the branch 15 conductors of an electric-railway system with the main conductor thereof, and it is more especially designed and adapted for use with the system of electric railways described and shown in United States patents granted to 20 me July 22, 1890, and numbered 432,673, 432,674, and 432,675.

The invention consists in the novel form of switch and water-tight switch-box, all as hereinafter more fully described, and then pointed 25 out in the claims.

In the accompanying drawings, illustrating my invention, and in which like letters and numbers of reference indicate like parts throughout, Figure 1 is a view of my novel 30 form of switch, the top of the switch-box being removed, so as to expose the various parts of the switch, and the pick-up arm or lever by which the switch is operated being shown in part and in elevated position, under which condition the switch is closed. Fig. 2 is a sectional view of the switch, the switch-box, and the operating pick-up lever, together with its casing, the switch being shown in closed condition and the plane of the section being indicated by line 2 2 in Fig. 1. Fig. 3 is a side view of the casing of the operating pick-up 40 lever, the lever being shown in elevated position. Fig. 4 is a detailed view in section of parts of the apparatus hereinafter referred to.

Referring to the drawings, 6 designates a 45 casing made of any suitable metal or material and formed with a chamber 7, in which swings the pick-up arm or lever 8, by which is operated the switch connecting the branch 50 conductor with the main. The pick-up lever 8, which may be made of wood or any other suitable material, is swung on a shaft 9 by

means of the flanged sleeve 10. In case the pick-up lever should be made of a material that would have to be insulated from the shaft 55 9, the sleeve 10 may be made of suitable insulating material, and may also serve to prevent water from working its way along the shaft toward the switch-box. The pick-up lever 8 is made fast to the shaft 9, which 60 turns in its bearings formed in the casing, and is designed and adapted to be moved in and out of the opening 11 of the chamber 7, and it consists, in general, in a broad flat plate, which may be elevated into the position shown 65 in the drawings in order to close the switch and may be lowered so that its upper edge may lie in about the same plane or be flush with the upper part of the casing 6. The pick-up lever by its own weight will gravitate 70 into the lowest position when free to do so, the switch under this condition being open, as indicated in dotted lines in Fig. 1.

Upon the free end of the pick-up lever 8 is fixed a contact-piece 12, with which is connected an insulated branch conductor *a*, which, through means of the switch hereinafter to be described, is connected with another portion of the branch conductor *b*, which leads to an ordinary main conductor. (Not shown.) 75 The branch conductor *a* is suitably secured to the pick-up lever and extends along the same from the contact 12 to the shaft 9, passing through an opening 13 in the latter into a recess 14, formed centrally in said shaft. 80 In the end of the recess 14 is fitted an insulating and water-tight plug 15, through which the conductor *a* extends into the switch-box to the binding-posts 16 and 34, the said plug extending through an opening 45 in the switch-box. The other part *b* of the branch conductor leads from the shaft or stud 17 through the insulating plug 15 into the recess 14 of the shaft 9, thence through an opening 18 in said shaft to and through an opening 19 in 95 the hub or collar 20 of the switch-box 21, and thence to the main conductor before referred to, the switch-box being secured upon the end of the shaft 9 by means of the screw 22, so as to turn with the shaft. This switch-box 21 is 100 a hollow drum, the inner face of which is provided with a hub or tubular projection 20, by means of which it may be fitted upon the end of the shaft 9. The other side of the switch-

box is removable, consisting in a circular plate 23, which is detachably secured upon the box by means of screws 24, a water-tight joint being formed between the cover and the box. 5 A washer 40 is placed between the ends of the collar 20 of the switch-box and the flange 41 of the bearing of the shaft 9 in the casing 6, so as to form a water-tight joint. The switch-box is inclosed above and at two sides thereof by 10 means of the bracket or housing 25, which is secured upon the casing 6, being either cast therewith or made separate therefrom and secured to the casing by any suitable means.

Within the switch-box 21 is mounted a fixed 15 shaft or stud 17, which is secured by screws 26 to an insulating-plate 27, made fast to the inner side of the switch-box by the screws 28. Upon the shaft 17 is swung a pendulous circuit-completing arm 29, which is adapted to 20 swing back and forth between the positions indicated in full and dotted lines in Fig. 1 in response to the movements of the pick-up lever 8. This arm 29 swings on a center eccentric to the center upon which the pick-up 25 lever turns, so that the movements of the latter may translate or carry the arm back and forth within the limits of movement indicated in full and dotted lines in Fig. 1. The end of the arm 29 is provided with a suitable 30 weight 30 for causing it to swing freely and quickly, so as to make and break contact with a snap action. The contact or terminal plate 31 is secured to the pendulum 29 by a bolt 32, and it makes contact with a similar contact 33, which is secured by means of a set-screw 35 upon the binding-post 34, which is mounted upon an insulating-plate 36, located 35 upon the side of the switch-box eccentric to the axis about which the pick-up lever 8 turns. The post 34, carrying the contact 33, is electrically connected with the binding-post 16 through means of the branch conductor *a*. The contacts 31 and 33 are 40 adjusted relatively so that their ends come 45 flatly together when the switch is closed, as shown in the drawings. These contacts may be adjusted or set in proper position by means of the screws by which they are mounted.

In order to insure good electric connection 50 between the shaft 17 and the pendulum 29, which swings thereon, I provide the arm with a spring-plate 37, which is attached thereto at one end by the screw 38 and has its other end pierced by a screw 39, fastened in the end 55 of the shaft 17. The path of the circuit from the contact 12 to the main conductor, which is in this class of railways usually buried in the road-bed and suitably insulated, is by the insulated branch *b* to shaft 17, the swinging 60 arm or pendulum 29, contacts 31 and 33, post 34, and branch conductor *a* to contact 12 upon the end of the pick-up arm 8. In the use of this device in the way I intend to apply it in my system of electric railways the casing 6 is placed 65 in the ground, as indicated in Fig. 3, so that the top thereof comes flush with the surface of the road. The casing 6 may be parallel with the

rails of the track or at right angles thereto, according to the character of the pick-up arm 8 and its contact device 12. In the present construction the casing 6 is placed lengthwise of the track—that is, parallel thereto—so that the pick-up device carried by the car (which is not shown) may strike the contact 12 of the swinging lever 8 and elevate the latter, so as to 70 close the switch, and thereby connect the branch conductors with the main. When the pick-up lever 8 is in its lowest position, the switch is open, so that the contacts 33 and 31 are moved apart, under which condition the 75 said contacts and the pendulum 29 are in the positions indicated by dotted lines in Fig. 1. As the lever 8 is gradually elevated the contacts 31 and 33 and the arm 29, carrying one of the same, are moved gradually from the 80 dotted-line positions into the full-line positions, so that by the time the pick-up lever 8 is elevated to its highest point of movement the contacts 31 and 33 of the switch will be 85 closed, thereby completing the circuit between 90 the main conductor and the contact 12 of the pick-up lever.

Since all parts of the branch conductor, as well as the main and all parts of the switch, are insulated and protected against water, 95 and since the contact-point 12 is not energized until the pick-up lever 8 carrying it is raised into its highest position, when it will be above the level of any ordinary surface-water, the circuit between the main conductor and the contact device on the car is insured against short-circuiting by surface-water. By virtue of having the contact 33 and the swinging contact-arm 29 mounted eccentrically to the axis about which the pick-up lever 8 swings 100 both of the contacts 33 and 31 are given a translatory movement, and thereby moved 105 apart when the switch is opened, as will be readily understood from Fig. 1.

Having thus described my improvements 110 in electric switches for connecting the branch conductors of an electric railway with the main conductor thereof, what I claim as my invention, and desire to secure by Letters Patent, is—

1. In an electric switch, the combination, 115 with a swinging operating-lever and a switch box or plate moving in fixed relation therewith, of contacts arranged upon said box or plate eccentrically to the center of movement 120 of the operating-lever, whereby the movement of said lever in one direction may serve to close the contacts and the movement thereof in the opposite direction may serve to open the contacts, substantially as and for the purpose set forth.

2. In an electric switch, the combination, 125 with a swinging operating-lever and a switch box or plate moving in fixed relation therewith, of a fixed contact and a swinging contact mounted upon said box or plate eccentrically to the center of motion of the said lever, substantially as and for the purpose set forth.

3. In an electric switch, the combination, with an operating-lever and a switch box or plate moving in fixed relation therewith, of a fixed contact disposed upon said box or plate 5 eccentrically to the center of motion of the said lever and a swinging contact also mounted eccentrically to the center of motion of the said lever, substantially as and for the purpose set forth.
4. In an electric-railway switch, the combination, with a swinging pick-up lever and a shaft turning therewith, of a switch-box secured to the said shaft so as to turn therewith, and a branch conductor leading from the 15 main through the switch-box to the pick-up lever and provided with contacts within the switch-box for making and breaking the circuit in response to the movements of the pick-up lever, substantially as and for the purpose set forth.
5. In an electric railway, the combination, with a swinging pick-up lever and a shaft turning therewith, of a switch-box secured to and moving with said shaft, and a branch conductor leading from the main through the 25 switch-box to the pick-up lever and provided with contacts within the switch-box for making and breaking the circuit, the said contacts mounted eccentrically to the axis of rotation of the switch-box, one of said contacts being mounted so as to swing, substantially as and for the purpose set forth.
6. In an electric railway, the combination, with a swinging pick-up lever and a shaft 30 therefor with which it turns, of a switch having a switch-box mounted upon one end of the shaft, so as to move therewith, and a branch conductor leading from the main through the switch-box and to the said lever and extending through the shaft, substantially as and for the purpose set forth.
7. In an electric railway, the combination, with a swinging pick-up lever and a shaft therefor with which it turns, the said shaft 35 being recessed or hollowed out at one end, of a switch having the switch-box secured to the recessed end of the shaft and rotating therewith, and a branch conductor leading from a main and extending into the shaft to the recess 40 thereof through the same into the switch-box, thence out of the switch-box through the recess, and thence out of the shaft to the pick-up lever, substantially as and for the purpose set forth.
8. In an electric railway, the combination, with a pick-up lever 8, provided with a contact, such as 12, and mounted fast upon a shaft 9, of a switch-box secured to said shaft and turning therewith, a switch within said 45 box which is opened and closed by the movements of the same, and a branch conductor leading from the main through the switch-box

to the pick-up lever and having the said switch located therein, substantially as and for the purpose set forth. 65

9. In an electric railway, the combination, with a casing 6, formed with a chamber 7, a shaft 9, extending across said chamber, and a pick-up lever 8, mounted fast thereon and located within the chamber, the said shaft 70 formed with a recess 14 in one end thereof, of a switch-box mounted upon the recessed end of the said shaft, and a switch therein which is opened and closed by the turning of the switch-box in response to the movements 75 of the pick-up lever, and a branch conductor extending from a main to the pick-up lever and passing through the said recess 14 of the shaft 9, substantially as and for the purpose set forth. 80

10. In an electric railway, the combination, with a swinging pick-up lever, of a switch-box 21, rotating therewith, and a switch within the box comprising a fixed contact, such as 33, and a swinging contact-arm 29, carrying 85 a contact, such as 31, substantially as and for the purpose set forth.

11. In an electric railway, the combination, with a swinging pick-up lever 8, of the switch-box 21, rotating therewith, and the switch 90 within the switch-box, comprising a fixed contact 33 and a swinging contact-arm 29, provided with a contact 31, a shaft 17, upon which the said arm 29 is mounted, a spring 37, secured to the said arm 29, and a screw 95 39, engaging the spring and secured to the end of the shaft 17 for electrically connecting the arm 29 with said shaft, substantially as and for the purpose set forth.

12. In an electric railway, the combination, with a casing 6, formed with a chamber 7, a shaft 9, mounted across the said chamber and formed at one end with a recess 14, and a pick-up lever 8, mounted fast upon said shaft, of a switch-box 21, mounted upon the recessed 105 end of the said shaft and formed with a central opening in alignment with the recess 14 of the shaft, a water-tight plug 15, placed through the said opening in the switch-box and extending into the recess 14, and a branch 110 conductor extending from the main into the said recess 14 of the shaft and through the plug 15 and thence from the switch-box back through the plug into the said recess and out through the shaft to the said pick-up lever, 115 substantially as and for the purpose set forth.

In testimony whereof I have hereunto set my hand, this 10th day of November, 1890, in the presence of the two subscribing witnesses.

FRANK MANSFIELD.
